UNITED STATES PATENT OFFICE

HARLEY E. GOODWIN, OF HARTFORD, CONNECTICUT

BATHTUB SEAT AND HAND REST

Application filed November 29, 1929. Serial No. 410,467.

My invention relates to a seat which may also be used as a safety hand-rest, and means for positioning same upon the outer and upper wall of bath-tubs.

5 The object of my invention is to provide a convenient and comfortable seat upon the edge or rim of bath-tubs, for greater ease in taking foot-baths whether within the bath-tub proper or by use of foot-tub or pan placed 55 within the bath-tub, as well as providing a convenient place to sit while drying the feet and lower limbs after bathing.

A further object of my invention is to provide in combination with the seat, a hand-rest, for greater safety and ease in getting in 15 and out of bath-tubs. It is well known that painful and often permanent injuries are frequently caused by slipping and falling in, and across the edges of bath-tubs, and this 20 I believe to be due in large measure to the bather depending for support upon the smooth or wet and slippery rail of tub. It will be readily understood that by making the upper side of seat and 25 hand-rest of rubber or other soft yielding material, that not only a comfortable seat, but a safe non-slipping rest and support for the hand is provided.

The invention further resides in ease of 30 manufacture and facility with which the device may be attached to practically all bath-tubs.

In carrying out my invention I make use 35 of the instrumentalities illustrated in the following figures, in which:

Figure 1 is a perspective view showing a section of side and upper portion of that type of tub having an outward and downwardly curving rail, and showing the seat in position 40 upon and over the rail, with its upper and outer sides visible, and likewise showing a detachable member inserted beneath the rail, and occupying that space between the outer wall of tub and the outside portion, or wing 45 of seat, together with two screws, one at either end of wing for the purpose of holding the inserted member in place.

Figure 2 is a side view of a section of the 50 upper side of a bath-tub as in Figure 1, with the seat mounted upon it, and the inserted

member held in position by screws passing through the lower or wing portion of seat at either end, and this inserted member is indicated as fitting underneath the curved rail or rim of tub. The upper portion of seat is indicated as being of considerable thickness and reduced somewhat in size at either end.

Figure 3 is much the same as Figure 2, but showing entire length of tub and indicating about the proportionate space the seat would 60 occupy.

Figure 4 is a cross sectional view of the seat and hand rest shown in Figures 1, 2, and 65 3, and showing the structure mounted upon the edge of the more modern type of bath-tub, which has its outer wall standing in a practically vertical plane, and without the overhanging curved rim or rail as shown in Figure 1. Also it will be seen that the inserted member held in position by screws beneath the curved rail as in Figure 1, is not required in Figure 4. Here the seat is shown as being fairly thick at the top as well as at its projecting or bulging upper sides and contracting as it extends downward in a wing or flange on both inner and outer sides of the tub wall. The center or inner structure of seat is indicated and may be described as being of suitable stiffening material and with a layer of rubber or other soft clinging substance where coming in contact with the tub wall, and having the outer and upper portions covered with rubber or other relatively thick, soft and yielding substance to provide 70 a comfortable seat surface.

80 My improved device in its general construction comprises a seat surface indicated by numeral 1 and this is intended to be practically flat and generally rectangular in shape, excepting at its extremities or corners 85 2—3—4 and 5 where it is reduced to conform more nearly to the shape of the top edge or rail 13 and 14 of bath-tub upon which it rests.

The seat portion proper 1, has outwardly 90 formed or bulging sides 6 and 7 to provide somewhat greater width than the usual bath tub rail discloses, and these protruding sides 95 6 and 7 contract somewhat abruptly and extend downward for a suitable distance upon 100

either side of the tub-wall 17 in the form of flanges or wings 8 and 9 as shown in Figure 4, which in general discloses the bath-tub seat positioned upon the outer wall 17 of a bath-tub of the more modern type.

5 In order that my bath-tub seat may be attached securely to that type of tub in more general use having an outward and downwardly curved top edge or rail and a relatively thin wall, I provide a member 10 as a 10 filler to be inserted between the tub wall 18 and the flange or wing portion of seat indicated by numeral 8. The member 10 is intended to fit against edge and concave portion of rail 13 and is maintained in its position by means of screws 11 and 12 passing through wing member 8.

15 The material construction of bath-tub seat and hand-rest, is best shown in cross section view of Figure 4, wherein the numeral 15 shows a core of sheet-metal, mesh-wire or other suitable stiffening material, and in contact with tub-walls a softer more clinging material as shown by numeral 16, and the 20 outer surface being covered with rubber or other suitable soft yielding material especially upon its upper side and indicated by numeral 19.

25 Having thus described the invention, what 30 is claimed as new, useful and patentable is:—

1. In a device of the character described a bathtub wall having an overhanging top rail, a combination seat and hand rest having downwardly extending wings engaging the 35 sides of the top rail portion, and a filler member positioned beneath the curved overhanging rail and detachably connected to the rest.
2. A combination seat and hand rest for bath-tubs having a body portion positioned 40 above the top of the wall of the bath-tub, wings depending from the body portion and adapted to straddle the wall of the tub, a reinforcing member straddling the tub wall and embedded in the wing portions, said 45 body portion having a generally flat top surface and the side edges of the body portion projecting laterally beyond the wing portions thereby providing a bulge at each side, the said body portion including the bulges 50 being tapered down at their ends whereby the ends of the body portion conform generally to the transverse curvature of the top of the bath-tub wall, and abrupt shoulders are avoided.

55 HARLEY E. GOODWIN.
